UNITED STATES PATENT OFFICE

168,983

CANASTA TRAY

Edwin L. Beckwith, West Newton, Mass., assignor to Beckwith Manufacturing Company, Dover,
N. H., a corporation of New Hampshire

Application September 26, 1952, Serial No. 21,607

Term of patent 14 years

(Cl. D34—13)

To all whom it may concern:

Be it known that I, Edwin L. Beckwith, a citizen of the United States, residing at West Newton, in the county of Middlesex and Commonwealth of Massachusetts, have invented a new, original and ornamental Design for a Canasta Tray, of which the following is a specification, reference being had to the accompanying drawing forming a part thereof, in which:

Fig. 1 is a view in perspective of a canasta tray in closed condition showing my new design.

Fig. 2 is a perspective view of the tray in open condition.

I claim:

The ornamental design for a canasta tray, as shown.

EDWIN L. BECKWITH.
